UNITED STATES PATENT OFFICE.

BENJAMIN PORTER, OF ELLENDALE, NORTH DAKOTA, ASSIGNOR OF ONE-HALF TO FRED L. WALKER, OF SAME PLACE.

HANGING LAMP.

SPECIFICATION forming part of Letters Patent No. 575,769, dated January 26, 1897.

Application filed March 11, 1896. Serial No. 582,806. (No model.)

To all whom it may concern:

Be it known that I, BENJAMIN PORTER, a citizen of the United States, residing at Ellendale, Dickey county, North Dakota, have invented certain new and useful Improvements in Hanging Lamps, of which the following specification contains a full, clear, and exact description, reference being had to the accompanying drawings, in which—

10 Figure 1 is a side elevation of my improved hanging lamp; and Fig. 2 is a similar view of a modified form, the lamp-bowl being omitted.

15 My invention relates to that class of hanging lamps which are adapted to be raised and lowered and commonly called "drop-lights."

20 The object of the invention is to provide a simple and inexpensive lamp of this character which may be detached from the hook or eye at the ceiling and carried from one place to another, and again attached to the ceiling hook or eye, and that without the use of a step-ladder. In the class of lamps suspended by chains or flexible devices the lamp cannot be detached from one ceiling-hook and carried to another 25 without having to mount a step-ladder, which is not only inconvenient but attended by more or less danger. My lamp, however, has a rigid, extensible, and contractible hanger held in any adjusted position by means of a clutch-spring, and it may be carried from one suspension-hook to another.

30 The invention will be first described, and then specifically pointed out in the claims.

35 A represents a lamp-bowl of any suitable construction and material, but I prefer a metallic bowl.

40 B represents the upper or stationary member of the hanger, and comprises two parallel rods B' B', either tubular or solid, an upper cross-piece B², having a hook or eye b², and a lower cross-piece B³, provided with guide-openings b³. The lower or sliding member B⁴ of the hanger comprises two parallel guide-45 rods B⁵ B⁵, which slide freely through the openings b³ and are connected at their upper ends by a cross-piece B⁶, which is provided with two end apertures b⁶, through which freely pass the rods B' B', so that said cross-piece may freely slide thereon.

50 The upper ends of the rods B⁵ pass freely

through apertures b⁵ in the cross-piece B⁶ and have a short sliding movement therethrough, the upward movement being limited by pins b⁷ or shoulders, which engage the under side of the said cross-piece, and the downward movement of the rods B⁵ being limited by heads b⁸ on their upper ends. These heads b⁸ project outwardly and upwardly in opposite directions toward the inner sides of the rods B', but do not contact therewith, and C is a 60 plate-spring riveted or otherwise secured at its middle to the upper arched middle portion of the sliding cross-piece B², and its ends curve upwardly and bite at their extremities upon the stationary rods B' B', so as to yield 65 and allow the sliding section B⁴ of the hanger to be pulled down and yet hold it in its adjusted position, the extremities of said spring being notched, as at c c, to prevent lateral disengagement.

70 When the section B⁴ of the hanger is pushed up, however, the upper ends of its rods B⁵ will slide through the cross-piece B⁶, and the releasing-heads b⁸ will engage the under side of the spring C and raise its ends out of engagement with the rods B', so that the sliding hanger-section may be raised to any desired height. As soon as the section B⁴ is released it will slide down and its heads b⁸ will become 75 disengaged from the spring C, which will 80 again bite upon the rods B' B' and hold the sliding section in its adjusted position.

75 The lower ends of the rods B⁵ B⁵ are provided with vertically-disposed loops b⁹ b⁹, which encircle the lamp-bowl A, and the lower 85 portions of these loops are rigidly connected by a handle D, spaced below the bottom of the lamp and having upwardly-projecting arms d d, secured to said loops.

80 E is a suspension-hook secured to the ceiling and from which the lamp is removably suspended by the eye b². By having these hooks in different parts of a room and in different rooms the lamps may be placed wherever desired, as it is only necessary to grasp 90 the handle D and raise the lamp as an entirety till the eye b² is disengaged from hook E and then carry the lamp wherever desired, the hanger remaining in its vertical position.

95 If the lamp is too high, it will only be neces- 100

sary to pull down gently on the handle, which will overcome the friction of the spring C against the rods B' and allow the sliding hanger-section B⁴ to slide down, and a push 5 on the handle D will cause the positive releasing of the spring C through the medium of heads n⁸ and allow the hanger-section B⁴ to slide up.

The handle D is spaced away from the lamp, 10 so as to prevent oil from soiling the hand when operating the hanger.

F is the usual bell or deflector suspended over the lamp-chimney from the cross-bar B³.

In Fig. 2 I have shown a modification of 15 the retaining-spring C, and in place thereof a spring C' is employed. This spring C' is secured at its inner end to the upper side of the cross-bar B³ and has an aperture c' and a slot c², through which pass a rod B⁵ and a rod B', 20 respectively, and from the outer end of the spring hangs an operating strand or chain C². The spring C' projects at an angle and its aperture c' engages with its outer wall, as at c³, the outer side of the rod B⁵, so as to frictionally hold it against downward movement 25 due to the weight of the lamp, but not with sufficient force to prevent the lamp from being pulled down to any desired position. In order to raise the lamp, the strand or chain C² 30 must be pulled upon to depress the spring C' and throw its edge c³ out of contact with rod B⁵, and then the lamp may be pushed up to any desired height, when the spring C' will be released and again clutch or grip the rod B⁵, 35 as before, and hold the lamp in its adjusted position. In this modified construction the upper ends of rods B⁵ are immovably secured to cross-piece B⁶. The slot c² is simply to allow the spring to straddle the bar B'.

40 Having thus described my invention, what I claim is—

1. The combination with the stationary hanger-section having parallel rods upper and lower cross-pieces of the sliding lamp-supporting hanger-section also having parallel connected rods and a plate-spring secured to one hanger-section projecting at an upward incline toward a rod of the other section and engaging said rod with sufficient force to hold 45 the lamp at any desired adjustment and yet yield to a downward pull on the lamp, and means for disengaging the spring from the said rod when the lamp is to be raised or pushed up, substantially as set forth.

55 2. The combination with the upper or stationary hanger-section having parallel connected rods, of the lower or lamp-supporting section having parallel rods in sliding engagement with said upper section; said rods having a limited sliding movement of their own independent of their movement on the said upper section, and a clutch or grip on the upper end of the lower section, engaging the upper section and in the path of the upper end 60 of said sliding rods, to be released thereby when the lower section is pushed up and given

its independent sliding movement, substantially as set forth.

3. The combination with the upper or stationary hanger-section having connected parallel rods, of the lower or lamp-supporting hanger-section having parallel rods in sliding connection with said upper section, a cross-piece connecting the upper ends of said sliding rods and in which said upper ends have 70 a limited sliding movement, a spring secured to the upper side of said cross-piece and frictionally engaging with its opposite ends the stationary parallel rods; the upward movement of the sliding rods causing their upper ends to bear against the lower side of said spring and press the ends of the spring out of engagement with said stationary rods, substantially as set forth.

4. The combination with the upper or stationary hanger-section having upper and lower connecting cross-pieces, of the lower or lamp-supporting hanger-section having parallel rods in sliding connection with said upper section and connected at their upper ends 80 by a cross-piece sliding on the stationary rods and through which cross-piece the upper ends of said sliding rods have a limited sliding movement, heads on the upper ends of the sliding rods and projecting toward the stationary rods, a spring secured at its middle to the middle of the upper side of said sliding cross-piece with its ends projecting outwardly and upwardly into engagement with the stationary rods just above said heads, substantially 90 as and for the purposes set forth.

5. The combination with the upper or stationary hanger-section and means for suspending it, of the lower hanger-section having parallel rods in adjustable sliding connection 105 with said upper section, lamp-receiving loops or yokes at the lower ends of the sliding rods and a transverse handle-bar, rigidly connecting the lower ends of said loops, substantially as set forth.

6. A hanging lamp consisting in the upper or stationary hanger-section having means for suspending it from a ceiling and provided with depending parallel rods connected at their lower ends by an apertured cross-piece, 115 the lower or sliding hanger-section having parallel rods sliding through said apertured cross-piece and provided at their upper ends with a cross-piece sliding on said stationary rods and in which cross-piece the upper ends 120 of said sliding rods have a limited sliding movement, heads on the upper extremities of the sliding rods, a spring secured to the sliding cross-piece above said heads to be raised thereby and engaging with its opposite ends 125 the said stationary rods, a lamp-bowl secured to the lower ends of the sliding rods, and a handle-bar beneath the bottom of the lamp and spaced therefrom, substantially as set forth.

7. The combination with the upper hanger-section having depending parallel rods, of the

lower, lamp-supporting hanger-section having vertical parallel rods and a cross-piece connecting their upper ends and sliding on the first-named rods, and a spring secured at 5 its middle to the said sliding cross-piece and in frictional engagement at its opposite free ends with said depending stationary rods to

hold the lamp-supporting section at any desired height, substantially as set forth.
